UNITED STATES PATENT OFFICE

WALTER KING, OF SAN JOSE, CALIFORNIA, ASSIGNOR TO SPRAGUE-SELLS CORPORATION, OF HOOPESTON, ILLINOIS, A CORPORATION OF DELAWARE

EXHAUST BOX

Application filed January 11, 1926. Serial No. 80,460.

My invention relates to devices used in the food packing industry for heating the cans or containers after they are filled and before they are capped, so as to exhaust the imprisoned air in the contents of the container.

One of the objects of the invention is the provision of an exhaust box embodying the disk type of conveyor, in which means are provided for shunting the cans from one portion of the conveyor to another portion thereof in order to vary the effective length of the conveyor.

My invention possesses other objects and features of advantage, some of which with the foregoing will be set forth in the following description of the preferred form of my invention which is illustrated in the drawings accompanying and forming part of the specification. It is to be understood that I do not limit myself to the showing made by the said drawings and description as I may adopt variations of the preferred form within the scope of the invention as set forth in the claims.

Referring to the drawings:

Figure 1 is a plan view of my exhaust box, the cover being removed and the end portions broken away to shorten the figure.

Figure 2 is a plan view of a portion of the exhaust box, drawn to a larger scale than Figure 1 and showing more clearly the guide rail structure.

Figure 3 is a detail in elevation, showing one of the brackets for supporting the steam pipes.

Figure 4 is a transverse vertical section, the plane of section being indicated by the line 4—4 of Figure 1.

Figure 5 is a transverse vertical section of a portion of the machine showing the bracket on which the guide rails and steam pipes are supported.

From one angle my invention may be regarded as a conveyor suitable for use in a variety of apparatus in which material is treated during the progress thru the apparatus and in which it is desired to vary the time required for the treatment. In the present application I have chosen to embody my invention in an exhaust box for heating the

cans after they have been filled, to exhaust the air from the contents.

In general terms my exhaust box comprises a housing in which a plurality of rows of tangentially arranged toothed carrier disks are placed. The disks provide means for conveying the cans thru the housing, and in alternate rows the disks revolve in one direction while in the other rows the disks revolve in the opposite direction. The disks in any one row are not in mesh with each other but with the two adjacent disks in the adjoining row. A drive shaft extending transversely across the rows below the disks is suitably geared to a disk structure preferably in two alternate rows, so as to distribute the strain of the driving force, all of the disks then acting as a single gear train driven by force applied at two different points in the train.

The driving shaft is driven thru suitable clutch mechanism by a pulley connected to any suitable source of power. The spacing of the disks is preferably such that a straight line drawn between the centers of rotation of corresponding disks in alternate rows is substantially tangent to the adjacent disks of the other rows.

Steam pipes for distributing jets of steam within the housing, are arranged coincident with planes cutting the centers of rotation of corresponding disks in alternate rows. These pipes are supported at their outer ends on suitable headers extending longitudinally of the outer row of disks, and at their inner end, each pipe terminates in a block which is supported on a bracket projecting upwardly from a transverse bar below the disks. There are a number of these bars which also serve to support the bearings in which the disks are journaled. Guide rails are arranged adjacent these pipes and in part are supported on the same brackets. The guide rails direct the cans on the disks back and forth transversely across the housing to the terminal disks which are of course the disks in the outer rows. The terminal disks receive the cans moving across the housing in one direction, carry them thru an arc of approximately 300°, and start them backwardly on the return trip across the housing. Movable sections are provided in

the guide rail which may be shifted into such a position as to permit the cans to remain on a disk in one of the intervening or inner rows long enough so that its direction of travel is changed; that is, the disk functions as a terminal disk to carry the can around and start it backwardly across the housing, thus shortening the distance thru which the can is carried by the length of the path across the disks skipped by the short cut.

Preferably these movable rail sections or switches are provided so that in a four-row exhaust box, two of the rows may be rendered inactive, if all of the switches are open, thus reducing the length of the can travel one-half. It will be obvious that with a setting of a different number of switches, practically any variation in the length of the can travel from one-half to the full distance is readily secured. If but one set of switches is opened the length of the path thru which the cans travel is shortened by an amount equal to the distance across the exhaust box. The opening of an additional set of switches, lessens the length of the can path by a similar amount. Thus the length of the path may be so fixed by the opening of the required number of switches that the time required for the material to pass thru the exhaust box is readily brought within the desired limit.

In detail my exhaust box comprises a framework including end rails 2 and side rails 3. Legs 4 are suitably braced by cross bars 6 to support the frame on the floor. Spaced transversely across the frame at suitable intervals are bars 7 which preferably are of rectangular section, and which are secured in the side frame members 3 by suitable brackets 8. Firmly clamped on these bars by the bolts 9 passing thru the caps 11 are the brackets 12, each of which is preferably integrally formed with a vertical bearing box 13. The brackets alternate on each side of the bar and in the present embodiment of my invention there are four brackets on each bar, altho six or eight may be used.

Journalled in each bearing box is a shaft 16 on the upper end of which is fixed the carrier disk 17, preferably slightly concave on its upper surface and provided on its periphery with the spur gear teeth 18 preferably beveled slightly on the upper side to facilitate the movement of the cans thereover.

The radius of each carrier disk is but little greater than the diameter of the largest container to be handled, and the arrangement of parts is such that in plan view, the disks are arranged in an even number of rows, preferably four or six, the disks in any row being out of engagement with each other but in mesh with two tangentially adjacent disks in the adjoining row.

Thus all the disks are geared together in a single gear train, and the direction of rotation of the disks in one row is opposite to

that of the disks in the adjoining row or rows. A line passing thru the centers of corresponding disks in alternate rows lies between and is substantially tangent to two disks in each of the other rows.

Since all of the disks are connected, driving one disk will drive the entire train, but in order to distribute the stress, I prefer to drive at two points. Two of the disks are each mounted on a shaft which extends

downwardly thru the bearing box and terminates in a bevel gear 22. Extending

across the machine below the gears 22, which preferably are arranged on shafts of disks in alternate rows, is a shaft 23 on which are fixed gears 24, which are in mesh with the gears 22.

The velocity of the shaft is cut down by connection thru the gears 26 with the drive shaft 27 between which and the driving pulley 28 is interposed the

clutch 29, controlled by the long rock shaft 31, having handles at the end of the machine so that the operator can quickly reach a control handle from any point about the

machine.

Extending longitudinally along the outer edge of the outer row of disks on each side, and supported on brackets 32 are header pipes 33 and 34. These pipes are joined by a cross pipe 36, below the disks which is connected by the pipe 37 with a suitable source of steam under pressure.

Extending from the pipe 33 transversely across the disks are pipes 38 placed a little above the surface of the disks and coincident with a vertical plane determined by the axes of rotation of corresponding disks in alternate rows.

The outer end of each pipe 38 is carried in the top of a bracket 39 projecting upwardly between the disks, and clamped at its lower end to the cross bar 7, on which adjustability is secured by the screws 41 so that the pipes may be properly aligned up with the disks.

In a similar manner pipes 42 are supported at one end in the header 34, and extend across the disks, between the pipes 38, to supporting brackets 43 similar to brackets 39.

There is this difference, however, between the pipes 42 and the pipes 38. The latter extend straight across the disks a short distance above them, but the pipes 42 are each provided with a goose neck, or raised

portion 44, which overlies the farther half of the disks over which the switches operate. This raised portion extends a sufficient distance above the surface of the disks to provide a free passage thereunder for the cans carried by the disks when the switches are open.

All the branch pipes 38 and 42 are perforated so that live steam is admitted into the exhaust box thru them.

Mounted on the brackets 46 fixed to the header pipe 33, and on the brackets 39 is a continuous guide rail 47, extending back and

forth across the disks. This rail overlies the outer portions of the peripheries of the terminal disks adjacent the header pipe 33, and extends closely adjacent opposite sides of the branch pipes 38 to the centers of the terminal disks on the opposite side. A similar rail 48 is mounted on the brackets 49 on the header pipe 34, overlying the outer portions of the peripheries of the adjacent terminal disks, and extending to the centers of the disks of the second row, where it is supported by the bracket 51 disposed on the branch pipe 42. The continuity of this rail is therefore interrupted for the farther half 36 of the disks in the second row, and these portions of the disks are the ones bridged by the goosenecks 44.

Beginning at the far end of each gooseneck and lying in alignment with the transverse 20 straight sections of the rail 48, are the rails 52, which extend to the centers of the terminal disks. Each of these rails is similar to the corresponding portion of the rail 48 and is supported by a bracket 43, and by 25 the lug 53, Figure 5, on the head 54 of the bracket 56, mounted like the brackets 39 and 43 on the cross bars 7.

Means are provided for insuring the movement of the cans back and forth across all 30 of the disk rows between the guide rails 47 on one side, and the guide rails 48 and 52 on the other, or optionally, insuring the movement of the cans back and forth across, say two rows only, between the guide rails 35 47 and 48; that is, switch rails are provided for shunting the cans under the gooseneck instead of permitting them to complete their movement across the housing, thus shortening one round trip across the housing by 40 about one-half. Jounaled in the head 54 of the bracket 56, and in the lug 57 thereon are two rock shafts 58 and 59, the former having a lever arm 61 fixed on its lower end. Fixed at the upper ends of the shafts 58 and 59 are switch rails 62 and 63 respectively, lying in the same horizontal plane as the 45 guide rails 48 and 52, and preferably curved on their adjacent sides as best shown in Figure 2. These switch rails are formed with gear teeth 64 which mesh together so that switch 63 is actuated by switch 62, and the movement of the two is uniform, opposite and simultaneous. An operating rod 66, pivotally connected to the end of each lever 61, 50 extends thru a collar 67, arranged on the side 68 of the exhaust box, and terminates in a knob 69. A set or wing screw 71 in the collar provides means for securing the rod, and the connected switch rails in adjusted 55 position.

Figure 2 shows one pair A of switch rails open to permit and insure the shunting movement of the cans around on the associated disk, under the gooseneck at that point, and 60 their delivery in a contrary direction to the

next disk. Thus the associated disk functions as a terminal disk and as to that particular round trip, the travel of the cans is reduced one-half. One pair B of switch rails is shown closed, and in this position they act to insure the continued movement of the cans and their delivery in the same direction to 70 the next disk.

In Figure 1, the first three pairs of switch rails are shown in open position the remaining pairs being closed. If all the switches were closed, the cans would travel eleven times across the exhaust box in the size of structure shown. To close the first three pairs of switches, each trip across for the 75 first six trips is reduced one-half so that the can travel is shortened by the equivalent of three trips, that is $3/11$ or about 27% of the maximum. The opening of all the switches would shorten the can travel $5/11$ or about 80 45%, and the opening of one switch would shorten the can travel $1/11$ or about 9%. With constant speed of the disks, these values of course also apply to the time of treatment 85 as well as length of travel so that by setting the switches, the time required for the cans to pass thru the exhaust box may be closely 90 regulated.

It will be observed that as the cans move 95 across the rows of disks, they pass from one disk, of which they are on one side of the center of rotation, to the next disk, of which they are transposed to the opposite side of the center of rotation, these disks revolving in opposite directions, and that this is true whether the cans travel across all four 100 rows or are shunted thru a short cut by intermediate switches.

At one end of the exhaust box a feed disk 105 73 is arranged, and on which the entering cans are placed. At the opposite end, a discharge disk 74 receives the treated cans and carries them forward to the next step.

In order to confine within the device the steam emitted from the branch pipes, side 110 walls 68 and end walls 76 are secured to the frame, extending upwardly far enough to clear the cans on the disks. The upper edges of the side and end walls are provided with a channeled edging 77; and a cover 78 having a down turned flange about its edge is fitted into the channel edging, so as to make an 115 easily removable tight closure.

In order to prevent leakage of steam from 120 the exhaust box, the space below the disks is closed by suitable pans 79, hung from the side frames on each side of the shafts 23 and 27. The space between the adjacent edges of the pans is filled with the inverted pan 81, supported on the side frame members.

I claim:

1. An apparatus for treating material comprising a conveyor including a plurality of disks arranged with the periphery of each disk adjacent that of an adjacent disk, and 130

- means for shunting the material from one portion of the conveyor to another portion thereof to vary the effective length of the conveyor.
5. 2. An apparatus for treating material comprising a conveyor including a plurality of disks arranged in planar alinement with the periphery of each disk adjacent that of an adjacent disk, and selective means for shunting the material from one disk to another to vary the effective length of the conveyor.
10. 3. An apparatus for treating material comprising a disk conveyor, and means for associating selected disks into conveyors of different length.
15. 4. In a conveyor comprising a plurality of cooperating circular units, means for associating selected units into conveyors of different length.
20. 5. In a conveyor arranged to move material thereon in a tortuous path, means for shunting the material across selected portions of the path to vary the effective length thereof.
25. 6. In a conveyor comprising a plurality of circular and tangentially arranged cooperating units, rails for guiding the material to be conveyed on said units, and selective means for varying the continuity of said rails to vary the effective length of the conveyor.
30. 7. In a conveyor, a plurality of cooperating units arranged in planar alinement, and movable guide means for varying the length of the path along which material on the conveyor moves.
35. 8. In a conveyor comprising a plurality of cooperating units arranged in planar alinement, movable guide means for correlating selected units into conveyors of different length.
40. 9. In a conveyor comprising a plurality of disks arranged with the periphery of each disk adjacent that of an adjacent disk, fixed rails for guiding the material to be conveyed on said disks, and switch rails for shunting the material over selected disks.
45. 10. In a conveyor comprising a plurality of disks arranged with the periphery of each disk adjacent that of an adjacent disk, rails for guiding the material to be conveyed on said disks and including pivotal portions adjustable to cause the material to move over selected disks.
50. 11. An apparatus for treating material comprising a housing, a conveyor arranged to move the material thru the housing, and means for positively shunting the material across selected portions of the path of movement.
55. 12. In an apparatus for treating material, a housing, a conveyor in said housing and including a plurality of tangentially arranged disks, and guide rails for correlating
- selected disks into conveyors of different length.
13. In an apparatus for treating material, a housing, a conveyor in said housing and including a plurality of tangentially arranged disks, fixed rails for guiding the material to be conveyed on said disks, and switch rails for shunting the material over selected disks. 70
14. In an apparatus for treating material a housing, a disk conveyor in said housing, fixed rails for guiding the material to be conveyed on said disks, switch rails for shunting the material over selected disks, and means operable from the outside of the housing for moving selected switch rails. 75
15. A conveyor comprising a plurality of disks, means for rotating the disks, guide rails for transferring material to be conveyed from the side of one disk to the side of an adjoining disk moving in the same direction and optionally operative guide rails for retaining the material on selected disks long enough to reverse the direction of movement of the material. 80
16. A conveyor comprising a plurality of rows of carrier disks, means for rotating the disks in alternate rows in one direction and in the other rows in the opposite direction, a guide rail overlying the disks to cause material on said disks to move back and forth across the rows to the terminal disks of the outer rows, and sections in said guide rail movable to overlie the periphery of a selected disk in the inner rows to cause that disk to 90 function as a terminal disk. 95
17. A conveyor comprising a plurality of disks, means for rotating the disks, a guide rail overlying the centers of the disks, and sections in said guide rail optionally movable to overlie the periphery of a selected disk. 100
18. In a conveyor, a carrier disk, and a guide rail optionally movable from a radial position relative to said disk to a position substantially in alinement with the periphery thereof. 110
19. In a conveyor, a carrier disk, a fixed guide rail extending radially to the center of the disk and a guide rail optionally movable from a position in alinement with the fixed rail to a position overlying and substantially in alinement with the periphery of the disk. 115
20. In a conveyor, a carrier disk, means for rotating the disk, and a rail optionally movable from a position for guiding material to be conveyed across the disk on one side of the center thereof to a position for guiding material thereon during at least one-half of its rotation. 120
21. In a conveyor, a carrier disk, a pair of pivotally mounted guide rails arranged adjacent the disk, means connecting said rails for unitary movement, and means for moving said rails. 125
22. In a conveyor, a carrier disk, a pair of 130

5 pivotally mounted guide rails arranged adjacent the disk, gear means connecting the rails for movement together, and means for moving said rails.

10 23. In a conveyor, a carrier disk, a pair of pivotally mounted guide rails arranged adjacent the disk, means connecting said rails for unitary movement, means for moving said rails, and means for locking said rails in position.

15 24. A conveyor comprising a plurality of rows of carrier disks, means for rotating the disks, a guide rail overlying the disks to cause material on the disks to move back and forth across the rows, a portion of said guide rail comprising a pair of pivotally mounted switch rails, means for connecting the switch rails for movement together, and means for moving the switch rails to vary the effective 20 length of the conveyor.

25 25. In a conveyor, a carrier disk, and a guide rail optionally movable from a radial position to a position in substantial alinement with the periphery of the disk to control the period of time during which the disk effects 30 the movement of the material to be conveyed.

35 26. In a conveyor, a carrier disk, and a guide rail optionally adjustable from a radial position on the disk to a position in substantial alinement with the periphery of the disk to control the path of movement of the material to be conveyed on said conveyor.

40 27. A conveyor comprising a plurality of tangentially arranged carrier disks, means for rotating the disks, and a rail pivotally mounted between the disks and movable to guide material to be conveyed over the disks in optionally selected paths of different lengths.

45 28. A conveyor comprising a plurality of rows of tangentially arranged disks, bars extending transversely below said rows and on which the disks are supported, means for rotating the disks, brackets on said bars extending upwardly between the disks, a guide rail supported on said brackets for causing articles on the disks to travel back and forth across the rows, a portion of said guide rail comprising a pair of switch rails pivotally mounted on one of said brackets, and means for moving the switch rails to vary the effective 50 length of the conveyor.

55 29. A conveyor comprising a plurality of rows of tangentially arranged disks, means for rotating the disks, a guide rail overlying the disks for causing material on the disks to travel back and forth across the rows and including switch sections movable to control the direction in which the material to be conveyed is transferred from the disks of the inner rows to the disks of the adjoining rows, and means for operating said switch sections.

60 30. An exhaust box comprising a housing, a plurality of carrier disks arranged in the housing, means for rotating the disks, an ad-

justable rail adjacent the disks for guiding articles thereover in optionally selected paths of different lengths, and means for adjusting said guide rail from the outside of the housing.

70 31. A conveyor comprising a plurality of carrier disks, means for rotating the disks, a stationary guide rail overlying the disks to cause material to move in a predetermined path across said disks, and a pair of switch rails normally forming a continuation of the stationary rail and pivotally mounted to permit positioning them in angular relationship to the stationary rail to shunt the material to a different predetermined path.

75 32. In combination with a disk conveyor, a switch rail pivotally mounted adjacent the edge of one of the disks, and means for optionally moving said switch rail to a radial position above the disk or for swinging the rail to a position overlying the edge of the disk.

80 33. In combination with a disk conveyor, a pair of switch rails pivotally mounted adjacent the edge of one of the disks, each of said switch rails being provided with gear teeth in mesh with those of the other switch rail, and a lever secured to one of said switch rails for moving the switch rails from a radial position on the disk to a position in substantial alinement with the periphery of the disk.

85 34. An apparatus for treating material comprising a conveyor positioned in a horizontal plane and including a plurality of disks arranged with their peripheries adjacent, and means for shunting the material from one portion of the conveyor to another portion thereof to vary the effective length of the conveyor.

90 35. The combination with a conveyor comprising a plurality of rotatable disks arranged with their peripheries adjacent, and guide means for directing a movement of material over all of said disks, of selective means for varying the effective length of the conveyor.

95 36. The combination with a conveyor comprising a plurality of rotatable disks arranged with their peripheries adjacent, and guide means for directing a movement of material in an undivided path over all of said disks, of selective means for varying the effective length of the conveyor.

100 37. The combination with a conveyor comprising a plurality of rows of disks, the disks of each row being tangentially arranged with respect to the disks of the adjacent row, and means for directing a movement of material over said disks, of selective means for varying the effective length of the conveyor.

105 38. An apparatus for treating material comprising a conveyor, including a plurality of disks arranged with the periphery of each disk adjacent that of an adjacent disk, means

for shunting the material from one portion of the conveyor to another portion thereof to vary the effective length of the conveyor, and means for guiding all of the material

15 along a selected conveyor length.

39. In a conveyor comprising a plurality of cooperating circular units, means for associating selected units into conveyors of different length, and means for guiding all of

10 the material along a selected conveyor length.

In testimony whereof, I have hereunto set my hand.

WALTER KING.
